OSCILLATORY SOOT BLOWER

Fred C. Arey, Oak Park, Ill., assignor to Vulcan
Soot Blower Corporation, a corporation of
Pennsylvania

Application November 1, 1933, Serial No. 696,174

9 Claims. (Cl. 257—1)

The present invention relates to soot blowers or cleaners in which the tubular blower or cleaning element swings about an axis other than its own long axis, and has for its object to simplify 5 and improve constructions of that type.

Viewed in one of its aspects, the present invention may be said to have for its object to simplify and improve soot blowers adapted to clean vertical tubes or flues in installations such, for 10 example, as air preheaters for furnaces or the like.

The various features of novelty whereby my invention is characterized will hereinafter be pointed out with particularity in the claims; but, 15 for a full understanding of my invention and of its objects and advantages, reference may be had to the following detailed description taken in connection with the accompanying drawing, wherein:

20 Figure 1 is a vertical section through an air preheater equipped with soot blowing apparatus embodying the present invention; Fig. 2 is a section on line 2—2 of Fig. 1; Fig. 3 is a top plan view, on a larger scale, of one end of the blower element, the flues being indicated in dotted lines; and Fig. 4 is a transverse section, on a still larger 25 scale, through the main portion of the blower element.

Referring to the drawing, A represents the casing or housing of a heat interchanger which is shown as being divided by a vertical partition B into two compartments one of which constitutes an air duct, and the other of which contains many vertical tubes or flues C arranged in transverse 30 rows. The lower ends of the tubes or flues are connected with and open out through a horizontal head D extending across the length and width of the compartment in which the tubes or flues are located. These parts may be of any usual or 35 suitable construction. Extending across the entire width of the casing or housing at a considerable distance below the plane of the head D and parallel with the transverse rows of tubes or flues, is a pipe or conduit 1. This pipe is 40 mounted in suitable bearings for angular movements about its axis. On one end of the pipe 1, outside of the casing or housing, is a suitable head 2 adapted to receive steam or other cleaning fluid through a supply pipe 3 and deliver it to 45 the said pipe or tube. This head is of the type that is adapted to turn the member 1 step by step 50 through definite, predetermined angles. Heads of this type are in common use, but I prefer to employ a head operating in accordance with the disclosure in my prior application, Serial No.

640,373, filed October 31, 1932. The head in the aforesaid application has a wheel or sheave that may be turned continuously in one direction or the other, causing a member corresponding to the member 1 to turn through a single step during each complete revolution of the wheel or sheave; the direction of the step by step movement being automatically reversed upon the reversal of the turning movement of the wheel or sheave.

5 In the arrangement shown, the member 1 is placed below the level of the floor E in the furnace room or boiler room, so that the blower head with its wheel or sheave 4 lies below the floor. An endless chain 5 passes around the under half of the wheel or sheave 4 and extends upwardly and over a second wheel or sheave 6 supported at such an elevation that it may conveniently be turned by hand by a workman. In the arrangement shown, the wheel or sheave 6 is fixed on a 10 horizontal shaft 7, parallel with the pipe or tube 1, which shaft is rotatably supported in a suitable bracket 8 projecting from the adjacent wall of the casing or housing. On the outer end of the shaft 7, beyond the wheel or sheave 6, is a suitable operating crank or handle 9.

15 The actual blower element is not the pipe 1, but a pipe or tubular element 10 lying parallel with the pipe 1 a short distance below the head D. This blower element extends between and is supported by the upper ends of radial tubular arms 11, 11 fixed to the pipe 1; these arms communicating at their lower ends with the interior of the pipe 1 and at their upper ends with the interior of the blower element 10. There may be 20 a tie member 12 arranged between the upper or outer ends of the arms 11, near and parallel with the blower element; this tie member being conveniently a pipe or tube so as to be light and yet 25 strong and rigid. The blower element is provided 30 with nozzles 14 distributed lengthwise of the same. As is customary in constructions of this type, the vertical tubes or flues in each transverse row are staggered with respect to those in the two adjacent rows. Thus, each of the odd numbered tubes or flues, reading from the left in Fig. 1, may be in the front row, while the others are 35 in the next row toward the rear. The nozzles on the blower element are therefore arranged in two rows, those in one row being shown in full lines 40 in Fig. 1 and those in the other row in dotted lines, because they lie behind the blower element, as viewed in Fig. 1. The arrangement of the nozzles is, of course, such that the blower element 45 may be placed in cleaning or blowing posi-

tion with respect to two adjacent transverse rows of vertical tubes or flues and thus cause these tubes or flues to be cleaned two rows at a time.

In moving the blower element across its entire sweep so as to cause all of the vertical tubes or flues within its range to be cleaned, the direction of the jets discharged by the nozzles will naturally vary according to the point at which the blower element happens to be in its arc of travel, if this element be fixed to the supporting arms. Obviously, this would prevent the jets from being discharged properly into all of the vertical tubes or flues. I have therefore provided means for turning the blower element relatively to its supporting arms, while these arms are swinging back and forth about the axis of the pipe 1, whereby the jets will always be discharged in the proper direction to enter the vertical tubes or flues for which they are intended; the blower element being for this purpose rotatably supported at its ends in suitable bearings in the arms. In the arrangement shown, the blower element is provided near each end with a pair of laterally-projecting ears 15, 15, while the supporting bearings 16, 16 for the pipe 1 are provided with similar pairs of ears 17; the ears 17 being stationary. Between each pair of ears 15 and the corresponding stationary pair of ears 17 is a rod or strut 18, pinned to both pairs of ears. Consequently, when the pipe 1 turns, the connections for the lower ends of the rods or struts 18 being fixed, the blower element must turn about its long axis. In other words, if a radius from the axis of the blower element through the point of connection between one of the rods or struts and the ears 15 is horizontal in a given position of the parts, this radius will always remain horizontal throughout the entire range of swinging movements of the device, and the directions in which the jets are discharged will always be parallel with the directions in any other position of the blower element.

The pipe 1 is provided with a second pair of radial arms 19, 19 extending downwardly therefrom; these arms being provided with weights, as indicated at 20, at their lower ends. The weighted arms balance the tubular blowing element and the means for supporting the same from the pipe 1, so that the device as a whole tends to remain in any angular position into which it may be moved.

Some of the vertical tubes or flues along the sides of the compartment containing the same overlie what may be termed the hollow supporting heads 21 on the upper ends of the tubular arms 11. In order that these tubes or flues may be properly blown, I provide the main blower element with short branch members 22, 22 rising therefrom and extending in the direction of the length of the same across the tops of the members 21. These branch blower elements are provided with suitable nozzles 23 that discharge jets into the lower ends of those vertical tubes or flues that cannot be reached by the jets from the main blower element.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a group of open-ended tubes or flues, a pipe mounted at some distance beyond

the ends of said tubes or flues with its axis transverse to the axes of the latter and adapted to turn about its own axis, a tubular blower element located near the open ends of said tubes or flues and paralleling said pipe, means supporting said blower element from said pipe for swinging movements about the axis of the latter and for placing the interior of the blower element in communication with the interior of the pipe, means for turning said pipe, and means to prevent the blower element from turning about its own axis during its swinging movements. 5

2. In combination, a group of open-ended tubes or flues, a pipe mounted at some distance beyond the ends of said tubes or flues with its axis transverse to the axes of the latter and adapted to turn about its own axis, a tubular blower element located near the open ends of said tubes or flues and paralleling said pipe, means supporting said blower element from said pipe for swinging movements about the axis of the latter and for placing the interior of the blower element in communication with the interior of the pipe, means for turning said pipe, and means for automatically causing relative turning movements between the blower element and the supporting means therefor while the blower element is making swinging movements. 10 20

3. In combination, a group of vertical open-ended tubes or flues, a horizontal pipe mounted at some distance below the ends of said tubes or flues and adapted to turn about its own axis, a horizontal tubular blower element located near the open ends of said tubes or flues, means supporting said blower element from said pipe and placing the interior thereof in communication with the interior of the pipe, means for turning said pipe, and means to prevent the blower element from turning about its own axis during its swinging movements. 30 35

4. In combination, a group of vertical open-ended tubes or flues, a horizontal pipe mounted at some distance below the ends of said tubes or flues and adapted to turn about its own axis, a tubular blower element located near the open ends of said tubes or flues, means supporting said blower element from said pipe and placing the interior of the blower element in communication with the interior of the pipe, means for turning said pipe, and means for automatically causing relative turning movements between the blower element and the supporting means therefor while the blower element is making swinging movements. 40 45 50

5. In combination, a group of vertical open-ended tubes or flues, a horizontal pipe mounted at some distance below the ends of said tubes or flues and adapted to turn about its own axis, a horizontal tubular blower element located near the open ends of said tubes or flues, means supporting said blower element from said pipe and placing the interior thereof in communication with the interior of the pipe, means for turning said pipe, and a counter weight balancing the weight of the blower element and the connecting means between the latter and the said pipe to cause the swinging structure as a whole to remain in any angular position into which it may be brought. 55 60 65

6. In combination, a group of vertical open-ended tubes or flues, a horizontal pipe mounted at some distance below the ends of said tubes or flues and adapted to turn about its own axis, tubular arms projecting upwardly from said pipe, 70 75

5 a tubular blower element extending between and rotatable in the outer ends of said arms, the parts being so constructed and arranged that the arms place the blower element in communication with the interior of the pipe, means for turning said pipe, and means for preventing the blower element from turning about its own axis while said pipe is being turned.

10 7. In combination, a group of vertical open-ended tubes or flues, a horizontal pipe mounted at some distance below the ends of said tubes or flues and adapted to turn about its own axis, tubular arms projecting upwardly from said pipe, a tubular blower element extending between and rotatable in the outer ends of said arms, the parts being so constructed and arranged that the arms place the blower element in communication with the interior of the pipe, means for turning said pipe, and a rod or strut hinged at one end to the blower element and at the other end to a stationary part beside said pipe, the effective length of the rod or strut being equal to the distance between the axes of the pipe and the blower element, and the distance between the upper hinge axis and the axis of the blower element being

equal to the distance between the lower hinge axis and the axis of the pipe.

15 8. In combination, a group of vertical open-ended tubes or flues, a horizontal pipe mounted at some distance below the ends of said tubes or flues and adapted to turn about its own axis, a horizontal tubular blower element located near the open ends of said tubes or flues, means supporting said blower element from said pipe and placing the interior thereof in communication 10 with the interior of the pipe, means for turning said pipe, means to prevent the blower element from turning about its own axis during its swinging movements, and a head associated with one end of said pipe to deliver to it a cleaning fluid and 15 to turn it step by step.

20 9. In a fluid heater cleaner, a tubular blower element having nozzles for discharging a cleaning fluid adjacent portions of a fluid heater to be cleaned, means to introduce cleaning fluid into 20 said element, means for oscillating said element about an axis apart from and parallel to its long axis, and means to turn said element about its long axis to maintain the nozzles directed toward the surfaces of the fluid heater to be cleaned. 25
